CLAIM

The ornamental design for a propeller blade as shown and described.

DESCRIPTION

FIG. 1 is a front-facing perspective view of a propeller blade according to the present design.

FIG. 2 is a rear-facing perspective view thereof.

FIG. 3 is a top view thereof.

FIG. 4 is a bottom view thereof.

FIG. 5 is a left side view thereof.

FIG. 6 is a right side view thereof.

FIG. 7 is a front view thereof; and,

FIG. 8 is a rear view thereof.

The dash-dash broken lines in FIGS. 1-9 are for the purpose of depicting unclaimed portions of the propeller blade and form no part of the claimed design.

In some examples the propeller blades illustrated herein are lift propeller blades. In some examples the propeller blades illustrated herein are propeller blades for electric aircraft. In some examples the propeller blades illustrated herein are lift propeller blades for electric aircraft.
